COMBINED CANOPY AND MULTIPLE SEATING UNIT FOR GOLFERS

Marcus S. Wise, 518 Cromer Ave., Muncie, Ind.

Filed July 6, 1964, Ser. No. 80,712

Term of patent 14 years

(Cl. D15—1)

FIGURE 1 is a perspective view of the combined canopy and multiple seating unit for golfers showing my new design;

The back of the canopy and the backs of the seats are plain and unornamented.

The dominant features of my design reside in those portions shown in full lines on the drawing.

I claim:

The ornamental design for a combined canopy and multiple seating unit for golfers, as shown and described.
